ELECTRICAL DISCHARGE APPARATUS

Karl Krause, Berlin, Germany; vested in the
Alien Property CustodianApplication July 9, 1940, Serial No. 344,568
In Germany March 18, 1939

9 Claims. (Cl. 250—27.5)

The present invention relates to electrical discharge apparatus such as cathode ray tubes and more specifically pertains to apparatus or arrangements for removing and replacing the cathodes of such apparatus without altering or destroying the vacuum or pressure within the discharge tube.

An object of the invention resides in providing means for mounting the cathode of electrical discharge apparatus on a movable carrier so that the cathode may be moved to a position for removal thereof from the carrier by simple and convenient means without affecting the pressure within the electrical discharge tube.

Another object of the invention resides in providing means arranged externally of the electrical discharge tube for removing a cathode from an operable position within the electrical discharge tube and replacing the removed cathode without altering the vacuum of the discharge apparatus.

Other and further features and objects of the invention will be readily apparent from a consideration of the accompanying drawing and following description wherein several exemplary embodiments of the invention are disclosed.

In the drawing:

Figure 1 is a sectional view of a portion of an electrical discharge tube illustrating apparatus for removing and replacing the cathodes thereof.

Fig. 2 is a sectional view of the apparatus taken on the line II—II of Fig. 1.

Fig. 3 is a sectional view of a modified arrangement for removing a cathode from an operable position in the electrical discharge apparatus.

Fig. 4 is a sectional view taken on the line IV—IV of Fig. 3.

Referring to the drawing there is shown in Figs. 1 and 2 a portion of an electrical discharge tube 14 which is provided with an anode 17. The apparatus includes a hollow rod 1 for supporting a cathode 2 within the end of the tube 14 as indicated in dotted lines in Fig. 1. The end portion of the hollow rod 1 is provided with a dove-tailed recess for receiving the tongue of the cathode 2.

The hollow cathode supporting rod 1 is slidably mounted within a guide member 3 which may take the form of a tube as shown in Figs. 1 and 2. The tubular guide member 3 is preferably arranged in axial alignment with the discharge tube 14. The hollow cathode supporting rod 1 may be moved within the tubular member 3 by means of a threaded shaft 16 and the manually operable handle 15 arranged beyond the end of the tubular member 3. The shaft 16 is provided with a

conical portion 18 which is sealed with respect to the tubular guide member 3. The cathode supporting rod 1 may therefore be retracted from the position shown in dotted lines in Fig. 1 to the position shown by full lines.

The discharge tube 14 is mounted on a housing member 13 and sealed with respect thereto in any well known manner and the housing 13 provides further means for guiding the cathode supporting rod 1.

A cylinder or sleeve 4 is arranged transverse to the guide member 3 and sealed with respect thereto as indicated by the welded joints adjacent the tubular guide member 3. The cylinder 4 projects laterally beyond both sides of the housing 13 as shown in Fig. 1. A plunger 7 is mounted for movement within the cylinder 4 and the end portion of the cylinder 4 illustrated to the right in Fig. 1 is sealed by means of the yieldable member 19 which may take the form of a bellows.

A plurality of new and unused cathodes 2a are stored adjacent the inner end of the plunger 7 within a housing 6. The housing is provided with a removable cover 11 and the new cathodes 2a are stacked therein so as to move downwardly by the weight thereof. Each new cathode 2a is provided with a tongue for engaging the dove-tailed groove provided in the cathode supporting rod 1.

The cylinder or sleeve 4 to the left of the tubular guide member 3 is closed and provided with a housing 10 which is also sealed by means of a removable plate 12.

When it is desired or necessary to replace the used cathode 2 the cathode supporting rod 1 is retracted to the position illustrated in full lines in Figs. 1 and 2. Thereafter the plunger 7 is forced inwardly with respect to the cylinder 4 so that the cathode 2a resting on the flat surface 8 of the plunger 7 is moved into engagement with the cathode 2 carried by the hollow supporting rod 1. When the plunger 7 has been moved to this position, the cathode 2a immediately above the cathode resting on the flat surface 8 is supported by a flat surface 9 also arranged on the plunger 7. Further movement of the plunger 7 to the left in Fig. 1 will force the cathode 2 from a supported position on the rod 1 and the cathode 2 may thus fall into the housing 10. During such movement of the plunger the tongue of the cathode 2a resting on the flat surface 8 is moved into the dove-tailed groove of the cathode supporting rod 1. When the plunger 7 is thereafter retracted the cathode 2a supported on the flat surface 9 will fall to rest on the surface 8.

The cathode supporting rod carrying the cathode 2a thereon may then be moved to the position shown in dotted lines in Fig. 1 or an operable position in the discharge tube 14. Thus it will be appreciated that the cathode of the electrical discharge apparatus has been replaced without altering or destroying the vacuum within the tube 14.

A modified arrangement for removing a used cathode is illustrated in Figs. 3 and 4 wherein the cathode supporting member 1a is provided with a series of tongues 21 for supporting a plurality of cathodes in a juxtaposed position as illustrated particularly in Fig. 4. In this modification the plunger for removing a used cathode 2b is indicated at 7a and the plunger 7a is adapted to engage the used cathode 2b as indicated in dotted lines in Fig. 4 so as to force the cathode 2b from the cathode supporting member 1a and move the cathode 2b into the housing 10. A new cathode 2c is thus uncovered so as to be capable of being moved into the discharge tube 14 by means of a threaded shaft similar to that shown at 16 in Fig. 1.

The bellows 19 for sealing the plunger 7a with respect to the cylinder 4 in Fig. 3 is preferably surrounded by a spring 20 so that the plunger 7a is retracted automatically.

While the invention has been described with reference to specific structural details it will be appreciated that changes may be made therein. Such modifications may be made without departing from the spirit and scope of the invention as set forth in the appended claims.

I claim:

1. An electrical discharge tube comprising, an electrode supporting member, a tubular guide member sealed with respect to the discharge tube for guiding said electrode supporting member into the discharge tube, an electrode removably carried by said supporting member, means for moving said electrode supporting member in the guide member, means sealing said tubular guide member, a cylinder mounted transversely of the tubular guide member, a plunger movable in said cylinder for moving said electrode from engagement with said supporting member, and means sealing said plunger with respect to the cylinder.

2. An electrical discharge tube comprising, an electrode supporting member, a tubular guide member sealed with respect to the discharge tube for guiding said electrode supporting member into the discharge tube, an electrode removably carried by said supporting member, means for moving said electrode supporting member in the guide member, means sealing said tubular guide member, a cylinder mounted transversely of the tubular guide member, a plunger movable in said cylinder for moving said electrode from engagement with said supporting member, a bellows sealing said plunger with respect to the cylinder, and a sealed housing carried by said cylinder for receiving the electrode removed from said supporting member.

3. Apparatus for removing an electrode of an electrical discharge tube comprising, a tubular guide member, an axially aligned housing member carried by the tubular guide member and mounted on the discharge tube, a hollow rod longitudinally movable in said guide member and said housing member, an electrode removably supported on said hollow rod, means for moving the hollow rod in said guide member and said housing member whereby the electrode may be moved into and withdrawn from the discharge

tube, a cylinder mounted on said housing member transversely of the tubular guide member, a plunger movably mounted in said cylinder for moving said electrode from supported engagement on said hollow rod, a yieldable bellows connected to and surrounding the plunger and closing an end of said cylinder, and means providing a closed chamber at the other end of the cylinder for receiving the electrode removed from the hollow rod.

4. Apparatus for removing an electrode of an electrical discharge tube comprising, an electrical discharge tube, a tubular guide member mounted on the discharge tube, a hollow rod longitudinally movable in said guide member, an electrode removably supported on said hollow rod, a threaded shaft engaging the hollow rod whereby the electrode may be moved into and withdrawn from the discharge tube, a cylinder mounted transversely of and sealed to the tubular guide member, a plunger movably mounted in said cylinder for moving said electrode from supported engagement on said hollow rod, a yieldable bellows surrounding the plunger and closing an end of said cylinder with respect to the plunger, and means providing a closed chamber at the other end of the cylinder for receiving the electrode removed from the hollow rod.

5. Apparatus for removing and replacing an electrode of an electrical discharge tube comprising, an electrical discharge tube, closed guide means in open communication with said discharge tube, a rod movable longitudinally in said guide means and having a dove-tail recess in an end thereof, an electrode having a tongue removably mounted in said recess, an encased plunger mounted for movement in alignment with said recess, a housing enclosing a plurality of auxiliary electrodes adjacent an end of said plunger, each of said auxiliary electrodes having a tongue for entering the recess in said rod, means on said plunger for moving the tongue of an auxiliary electrode into said recess and moving the tongue of the first-mentioned electrode from said recess during movement of the plunger towards said rod.

6. Apparatus for removing an electrode of an electrical discharge tube comprising, an electrical discharge tube, closed guide means in open communication with said discharge tube, an electrode supporting member movable in said guide means, an electrode carried by said supporting member and removable laterally therefrom, means for moving said supporting member in the guide means, a closed cylinder intersecting the axis of and carried by said guide means, and means movable in said cylinder and engageable with said electrode for moving the same laterally from the supporting member.

7. Apparatus for removing an electrode from an operable position within an electrical discharge tube comprising, an electrical discharge tube, closed guide means in open communication with said discharge tube, an electrode supporting member movable in said guide means, juxtaposed electrodes carried by said supporting member, each removable laterally therefrom, means in said guide means for moving the supporting member whereby an uncovered electrode may be moved to an operable position within the discharge tube and withdrawn therefrom, a closed cylinder on said tube intersecting the axis of said guide means, and means movable in said cylinder for engaging one electrode and moving the same laterally from the supporting member.

8. Apparatus for removing an electrode from an operable position within an electrical discharge tube comprising, an electrical discharge tube, closed guide means in open communication with said discharge tube, an electrode supporting member movable in said guide means, juxtaposed electrodes carried by said supporting member, each removable laterally therefrom, means in said guide means for moving the supporting member whereby an uncovered electrode may be moved to an operable position within the discharge tube and withdrawn therefrom, a cylinder mounted on the guide means and intersecting the axis of said guide means, a plunger movable in said cylinder for engaging one electrode and moving the same from engagement with the supporting member, a yieldable bellows sealing the cylinder with respect to the plunger, and a spring for returning the plunger to a retracted position.

9. Apparatus for removing an electrode from an electrical discharge tube comprising, an electrical discharge tube, a tubular guide member

mounted on said discharge tube, a hollow rod longitudinally movable in said guide member, an electrode removably supported on said hollow rod, means carried by said guide member for moving the hollow rod in said guide member whereby the electrode may be moved into and withdrawn from the discharge tube, a cylinder mounted transversely of the tubular guide member and sealed thereto, a housing mounted on the cylinder adjacent the guide member, a plurality of auxiliary electrodes within said housing, a plunger movably mounted in said cylinder, a flat surface on an end portion of said plunger for receiving an auxiliary electrode from said housing, a second flat surface carried by said plunger adjacent the first flat surface for retaining the other auxiliary electrodes within the housing during movement of the plunger towards said hollow rod whereby the electrode supported on the first flat surface may engage the electrode carried on said hollow rod to remove the same therefrom.

KARL KRAUSE.
